APPARATUS FOR GRINDING

Harold N. Seyferth, East Detroit, Mich., assignor to Ex-Cell-O Corporation, Detroit, Mich., a corporation of Michigan

Application October 6, 1943, Serial No. 505,098

2 Claims. (Cl. 51—165)

1

The present invention pertains to a novel apparatus for grinding metal work pieces.

Generally stated, the object of the present invention is to correlate in a novel manner the truing of a grinding wheel or other revoluble grinding element with the grinding operations performed thereby, to facilitate and improve successive rough and finish grinding operations.

I have discovered that there is a direct relation between the speed at which a grinding wheel or the like is trued and the character of the surfaces which it subsequently produces on a work piece. More particularly, if a grinding wheel is trued at high speed the effective cutting periphery of the wheel is more roughly dressed so that the wheel is free-cutting, a condition highly desirable for efficient rough grinding. On the other hand, if the same truing device is swept across the active periphery of the same wheel at a low speed which is but a minor fraction, for example, one-fifth of the high speed mentioned, the wheel will be dressed with a much smoother, less free-cutting surface which, in grinding, leaves on the work a smoother surface than in the case of the high speed truing. It is on the basis of these facts that the herein disclosed procedure is largely predicated.

Another object of the invention is to provide a novel electrical control system adapted to effect an automatic truing cycle in a grinding machine, correlated with the machine's general cycle of operation in such manner that the grinding wheel or the like is trued at high speed preparatory to the rough grinding pass or passes, and subsequently trued at low speed preparatory to the finish grinding pass or passes.

Further objects and advantages of the invention will become apparent as the following description proceeds, taken in connection with the accompanying drawing, in which:

Figure 1 is a generally schematic perspective view of a portion of a grinding machine equipped with an automatic dresser adapted for the present invention.

Fig. 2 is a wiring diagram of the dresser control for the machine of Fig. 1.

While the invention is susceptible of various modifications and alternative constructions, I have shown in the drawings and will herein describe in detail the preferred embodiment, but it is to be understood that I do not thereby intend to limit the invention to the specific form or series of steps disclosed, but intend to cover all modifications and alternative constructions and methods falling within the spirit and scope

of the invention as expressed in the appended claims.

The present invention is applicable to any one of the great variety of grinding machines which are known in the art and, accordingly, attention need not be given here to specific structural detail of the machine, as such. In Fig. 1 are indicated the principal elements commonly found, for example, in a center type grinder and which is one type of grinding machine to which the present invention is particularly suited. For further data as to the detailed structure of a representative machine of this type, reference may be made to my prior Patent No. 2,317,226, issued April 20, 1943.

In brief, a workpiece 10 is revolvably mounted between a headstock 11 and tailstock 12 which are carried on a table 14, the latter being reversely traversable in the usual manner axially of the work and the work being revolved by a suitable drive (not shown) in the headstock. Engageable with the periphery of the work piece is a rotatable grinding element, shown as an abrasive grinding wheel 15 adapted to be revolved by the usual drive motor (not shown) and carried toward and from the work, transaxially of the latter, by the supporting wheel slide 16 fed by a lead screw 17. In the usual manner, the wheel slide 16 may be fed forward by the screw 17, either manually or automatically, a small incremental step after each stroke or pass of the table 14 until the work has been ground to the desired depth.

As is also customary in grinding machines, provision is made for dressing or truing the wheel 15. In this case, the same has been indicated as including a single dressing point 18, although of course a plurality may be employed if desired, together with a dresser mechanism 19 driven by a reversible electric motor 20 for actuating the dresser mechanism to sweep the dressing point back and forth across the wheel periphery in a fixed path calculated to true or dress it to a desired contour. Rotation of the motor 20 in one direction causes the mechanism 19 to shift the tool 18 in a corresponding direction, and reverse rotation of the motor causes the tool to be moved through a corresponding return stroke. Dresser mechanisms, as such, are well-known in the art and the mechanism 19 may take any desired one of various well-known forms, and as a specific example reference may be made to Gilbert Stewart Patent No. 2,311,263, issued February 16, 1943. The motor 20 is belted to a speed reduction gearing within the casing 21 and is thence connected

anism. A dresser slide 23 supports the dresser mechanism on the wheel slide for movement into and out of operative relation with the wheel.

In accordance with the present invention, the speed at which the dressing or truing tool 18 is moved across the wheel periphery by the dresser drive motor 20 is correlated with the grinding operations in such manner as to condition the wheel successively for rough and finish grinding in operating upon the work piece. For a full understanding of how that is accomplished, attention should first be given to certain characteristics of grinding wheels or other revoluble grinding members of the class here contemplated.

It is contemplated that the grinding wheel shall consist of abrasive particles bonded or held together by a suitable binder. Wheels of great variety are, of course, used in the art, differing from each other in the abrasive used, the size of the abrasive particles, and the degree of strength with which the particles are bonded together by the particular one of the various available binders which may be used. Such wheels may vary from very hard, dense structures to comparatively soft ones which crumble readily under pressure. It is characteristic of such wheels, however, that the abrasive particles remove metal from the work in minute, and, in fact, many times microscopic, chips as the abrasive particles are dragged across the work surface by the wheel. When the wheel is roughly dressed it is said to be "free cutting," and is capable of removing comparatively large amounts of metal as the surface of the wheel is moved across the work. When the wheel is dressed with a smoother surface the cutting action on the work is correspondingly reduced and a smoother surface is produced on the work piece until a point is reached at which the wheel has largely a rubbing or burnishing action on the work.

I have found that with any given wheel, the freedom with which it cuts can in large measure and with reasonable accuracy be controlled through variation in the speed at which the dressing tool is moved across the wheel in truing the same. What apparently occurs is that if the dressing tool point is swept across the wheel periphery at high speed, the abrasive particles are uprooted so that a freely cutting surface results. On the other hand, if the dressing speed is diminished to a low value which is but a minor fraction, for example, one-fifth or one-fourth of the high speed, a much smoother wheel surface, suited to finish grinding, is produced. After the slow speed dressing, the wheel periphery has an appearance of being filled, that is, the interstices between the particles of abrasive appear to be filled and the tendency of the wheel to crumble is reduced. Merely by way of example, if the dressing tool is moved through a travel of $\frac{1}{16}$ of an inch during truing, it may be moved at a fast speed in conditioning the wheel for roughing such that it completes its truing travel in from three to nine seconds, whereas in conditioning the wheel for finishing the truing tool may be moved through the same length of travel at a comparatively slow speed requiring from sixteen to forty-eight seconds. The particular speeds chosen will be governed by the characteristics of the particular wheel which is used, the characteristics of the truing tool, etc.

In utilizing the foregoing phenomena, the general procedure which I employ is to carry out what is otherwise a normal grinding cycle except that the grinding wheel is trued at high speed

preparatory to the roughing passes, thus producing a freely cutting surface for that purpose, and is trued at a comparatively low speed preparatory to the finish pass. Specifically, the grinding may be carried out with reverse traversing of the work table 14 (Fig. 1) and incremental infeed steps of the wheel slide 16 after each pass of the work. Each time that a selected number of passes of the work, that is, one or more, has occurred, the dresser mechanism 19 is operated through a predetermined cycle by its drive motor 20 running at high speed, thereby effecting a high speed truing of the wheel 15 suited to rough grinding. When the total infeed of the wheel slide 16 is completed to a predetermined depth commensurate with the desired final size of the work, but before the last pass of the work, the dresser mechanism 19 is operated through its cycle with the dresser motor 20 running at low speed so as to condition the wheel 15 for finish grinding of the work in the final pass of the latter.

As indicated above, the alternation between high and low speed dressing is desirably accomplished by a corresponding alteration in the speed of the dresser drive motor 20. The speed of rotation of the wheel itself may be the same during both types of dressing. That same wheel speed may also be retained throughout both the rough and finish grinding operations, although in many instances it may be desirable to diminish the wheel speed during the finish grinding to avoid burning the work.

Attention may now be given to Fig. 2 wherein is shown the novel electric control circuit for carrying out the described cyclic changes in dressing speeds automatically. Included in this circuit are several contactors and relays and in each instance their contacts have been shown as connected at the proper points in the circuit, as well as duplicated at points adjacent the actuating windings to indicate their relation to the latter. These include forward and reverse contactors DF and DR having respective main contacts DF1, DF2 and DF3 and DR1, DR2 and DR3 interposed between the dresser drive motor 20 and three phase supply lines L1, L2 and L3 in the usual manner to effect rotation of the motor in respective opposite directions upon closure of corresponding ones of the contactors. These contactors are also provided with respective normally closed auxiliary contacts DF4 and DR4 for interlocking purposes plus normally open contacts DF5, DF6 and DR5 for control and interlocking purposes. Pilot lamps 24 and 25 are shunt-connected with the respective contactor actuating windings DF and DR to indicate when such windings are energized. Also included in the supply circuit of the dresser motor are the contacts F1 and S1 of what may be termed the fast and slow contactors F and S and which condition the two speed dresser motor alternatively for fast or slow speed operation upon closure. Finally, there are three control relays CR1, CR8 and CR10 whose functions in the circuit will appear below. All of these contactors of the relays are arranged to be energized by current derived from supply lines L1, L3.

As a means of instituting operation of the dresser after each predetermined series of one or more passes of the work, a counter mechanism of conventional design may be employed. In Fig. 2, the clutch coil and actuating coil of such a counter mechanism are indicated, respectively, at A and B, the latter mechanism having a normally open contact C which is closed upon the comple-

tion of each predetermined series of strokes of the table 14 which are being counted.

Various control switches are also included in the system. These comprise the switch LSS1 which is actuated from the feed screw from the wheel slide 16 and is closed upon completion of the incremental infeed of the wheel slide to a point corresponding to the desired depth of cut on the work. Also included is a table switch 26 which is closed whenever the table 14 is in motion. A manually operated selector switch 27 serves when opened to disable the counter mechanism, while a normally open push button switch 28 conditions the circuit for manually controlled operation upon closure. For use in conjunction with the push button switch 28 is a manually operable selector switch 29 having two sets of contacts 30 and 31, the former being shown as closed and the latter as open. When the switch 29 is positioned as shown, the circuit is conditioned for slow speed operation, while shifting the push button 29 to its alternate position conditions the circuit for fast operation of the dresser motor under the control of the push button 28 and irrespective of the position of the switch LSS1.

To condition the circuit of Fig. 2 for automatic operation, the switches are positioned as shown. In such case when current is applied to the circuit from the supply lines, the clutch coil A of the counter mechanism is energized, conditioning the counter for operation, and the actuating winding B of the counter is also energized, thereby advancing it one half step. The control relay CR1 is also energized through normally closed contacts CR10-1 of the relay CR10, sealing itself in through its own contacts CR1-1. The closing of its contact CR1-2 has no effect on the circuit at this point. As soon as the work table 14 starts to move in its first stroke, the table switch 28 is closed, thereby energizing the relay CR8 so that it opens both of its normally closed contacts CR8-1 and CR8-2. The former interrupt the flow of current to the counter actuating winding B, while the latter prevent institution of the dresser drive while the table 14 is in motion. As soon as the table comes to rest at the end of this stroke, the switch 28 is reopened, thereby deenergizing the relay CR8 so that its contacts reclose, thus applying another current impulse to the counter's actuating winding B. Each application of current to the winding B advances the counter one step so that the counter is actuated for each stroke of the table.

After a predetermined number of actuations of the counter, it closes its switch C, the latter remaining closed until reopened by starting of the dresser motor 20. Such closure of the switch C takes place coincident with the reclosure of contact CR8-2 at the end of a table stroke, wherefore a circuit is completed from line L3 through contact CR8-2 and switch C to the forward contactor DF for the dresser motor. The contactor thereupon closes its main contacts, seals itself in through its auxiliary contacts DF5, opens its interlock contacts DF4, and closes its contacts DF6 to complete an energizing circuit for the fast contactor F. Such closing of the contactors DF and F energizes the dresser motor 20 for rotation at fast speed in a forward direction.

At the completion of a predetermined forward movement of the dresser tool 18 by the dresser mechanism 19, a limit switch LSDF associated therewith is opened and a second limit switch LSDR closed. The opening of the limit switch LSDF drops out the forward contactor DF, while

the closing of the other limit switch LSDR picks up the reverse contactor DR. The fast contactor F remains energized, or is reenergized by closure of the auxiliary contacts DR5 on the reverse contactor, so that the dresser motor 20 is caused to revolve rapidly and in an opposite direction, thus driving the dresser mechanism reversely at high speed. At the end of the reverse stroke of the dresser tool 18, the reopening of the limit switch LSDR drops out the reverse contactor DR, and the other limit switch LSDF is reclosed. Such reclosure of the latter switch is ineffective to pick up the forward contactor DF, however, since the counter switch C was only momentarily closed and has now reopened. Consequently, the dresser mechanism comes to rest after the truing tool 18 has moved forwardly and reversely at high speed through a path determined by the dresser mechanism 19.

The high speed actuation of the dresser tool 18 through a preset cycle of motion in the manner described above dresses the periphery of the wheel 15 for free cutting action suitable for rough grinding. Such high speed dressing of the wheel is repeated periodically in accordance with the setting of the counter mechanism throughout the series of passes of the work piece 10 for completing the amount of rough grinding desired.

At the completion of the infeed movement of the wheel slide 16, or, in other words, upon the completion of the movement of the wheel slide inward to a position corresponding to the final depth of cut desired on the work but before the table 14 makes its last pass, the switch LSS1 is closed momentarily. This results in a momentary energization of the control relay CR10 during which the latter opens its contacts CR10-1 and CR10-4 and closes its contacts CR10-2, and CR10-3. When closed, the contacts CR10-2 act in conjunction with the previously closed contacts CR8-2 and CR1-1 to complete an energizing circuit for the forward contactor DF. This contactor picks up, sealing itself in through its contacts DF-5 as before. In this instance, however, the opening of the contacts CR10-4 and closing of CR10-3 disables the fast contactor F against energization and completes a circuit for the other or slow contactor S. The dresser motor 20 is thus energized for slow operation in a forward direction so that the truing tool 18 is moved slowly across the wheel periphery to true the wheel for finish grinding during the final stroke of the table which is to follow.

At the end of the slow forward movement of the truing tool 18, the switch LSDF is opened and the companion switch LSDR closed, whereupon the dresser motor 20 is energized for reverse movement, but again at slow speed. At the end of the reverse movement of the truing tool 18, the switch LSDR is reopened to drop out the reverse contactor DR and the companion switch LSDF is reclosed. The dresser motor comes to rest, however, since the relay CR1 has been dropped out by opening up contacts DF4 during the reversing of the dresser, wherefore reestablishment of the circuit for the forward contactor DF is prevented by the opened contacts CR1-1 when the switch LSDF recloses. After the last pass of the work table 14 during which the work is finish ground by the slowly trued wheel, the wheel slide 16 is retracted to its starting position, whereupon the switch LSS1 reopens and the dresser control circuit is thus restored to its initial position.

Should manually controlled operation be de-

sired rather than the automatically instituted operation described, as for example in setting up the dresser mechanism, the switch 27 may be opened to disable the counter and the push button switch 28 closed with the switch 29 shifted for either fast or slow operation as desired. With the switch 29 in the position shown, that is, with its contacts 30 closed and 31 open, closure of the switch 28 energizes the forward contactor DF, this being followed by closure of the fast contactor F so that the dresser motor 20 starts in a forward direction at high speed. It then executes its forward and reverse cycle as before. On the other hand, if switch 29 is shifted to its alternate position and the relay CR10 picked up by manually or otherwise closing LSS1, then closure of switch 28 will cause the dresser to execute a slow speed cycle of forward reverse. For either a slow or fast speed cycle, only a momentary closure of the switch 28 is required to constitute it since the forward contactor seals itself in by its contacts DF-5 in shunt with the switch 28.

I claim as my invention:

1. A dresser control system for a grinding machine having a work support and rotatable abrasive element, arranged for relative reciprocation axially of the element and for relative infeed with respect to each other transversely of the path of reciprocation, as well as a dressing tool for the abrasive element arranged to be swept to and fro across the abrasive element in a predetermined cycle of movement by a reversible electric dresser drive motor to dress such element, said control system comprising, in combination, a counter mechanism, means for actuating said counter mechanism in response to successive relative reciprocations of the work support and

- 5 abrasive element, means operable in response to each completion of a predetermined series of actuations of said counter mechanism for energizing said dresser drive motor to move the dresser tool through its cycle of movement at high speed, to thereby dress the element by each such cycle for rough grinding, and means operable in response to a preselected relative infeed of the work support and abrasive element for energizing said 10 dresser drive motor to move the dresser tool through its cycle of movement at a low speed which is but a minor fraction of said high speed, to thereby prepare the element for finish grinding of the work.
- 15 2. A dresser control system for a grinding machine having a work support and rotatable abrasive element, arranged for relative reciprocation axially of the element and for relative infeed with respect to each other transversely of the path of reciprocation, as well as a dressing tool for the abrasive element arranged to be swept to and fro across the abrasive element in a predetermined cycle of movement by a reversible electric dresser drive motor to dress such element, said control system comprising, in combination, means operable in response to the completion of a predetermined series of relative reciprocations of the work support and abrasive element for energizing the dresser drive motor to move the dresser tool through its cycle of movement at high speed, and means operable in response to a preselected relative infeed of the work support and abrasive element for energizing said dresser drive motor to move the dresser tool through its cycle of movement at a low speed which is but a minor fraction of said high speed.

HAROLD N. SEYFERTH.
